LIPSTICK LINER OR THE LIKE

Lester H. Howell and Lillian Howell, both of 816
Faysmith Ave., Torrance, Calif. 90503

Filed Apr. 25, 1968, Ser. No. 11,618

Term of patent 14 years

Int. Cl. D28—03

U.S. Cl. D86—10

FIGURE 2 is another perspective view thereof showing the protective cap removed to expose the tip portion of the new lipstick liner; and

We claim:

The ornamental design for a lipstick liner or the like, substantially as shown and described.
